UNITED STATES PATENT OFFICE.

PERCIVAL A. GOULD, OF GIBSONBURG, OHIO.

ARTICULATOR.

Application filed June 22, 1925. Serial No. 38,626.

This invention relates to prosthetic dental apparatus but more particularly is concerned with articulators.

In making artificial dentures considerable difficulty has been encountered in obtaining natural articulation and numerous mechanical devices have been designed for this purpose. Among these devices is an articulator produced by Alfred Gysi, commonly known as "the simplex articulator" and which has been popularly received by dentists throughout the country, but although this articulator performs fairly satisfactory work, it has failed to cope with an important and difficult problem which is outstanding as a matter of practice and which materially detracts from efficient performance.

Experiments have proved that the human mandible in every instance has a lateral or sidewise movement as well as a downward and outward protrusion and also that the rotation points of the mandible are located below and behind the condyles, these rotation points being the theoretical centers of motions exhibited in the human mandible. In view of these empirically discovered facts Gysi evolved his articulator and produced mechanically the movements of the human mandible.

In the Gysi apparatus there is provided a vertically disposed pin which is known as the incisor guide pin and this pin is connected for movement with a member (model support) corresponding to and movable in accordance with the human mandible. The guide pin engages a stationary guide and in practice the guide pin is moved back and forth as well as sidewise to position the artificial dentures relatively to each other, it being understood that the plates are mounted respectively on a stationary model support to which the guide is connected and the model support corresponding to the human mandible. If the patient for whom the dentures are intended is of the average and bites with an even muscular force on both sides, such dentures usually prove satisfactory.

Experience has shown however that dentures articulated in accordance with the Gysi apparatus are not satisfactory in about fifty percent of the cases and this is essentially because invariably persons do not have the same angular movement of the lower mandible and do bite on both sides with an equal

muscular force and therefore if the artificial dentures are articulated with the assumption that such force is equal on both sides, and the angular movement is of the average the dentures are not accurate. If the dentures are not articulated with these facts in mind and due compensation made therefor, the side which is subjected to the greater muscular biting force, is exposed to absorption and this militates against proper fitting so that after a comparatively short time the dentures will not remain in the mouth.

Objects of this invention are to overcome the above difficulty; to provide a simple and inexpensive articulator in which artificial dentures may be articulated accurately irrespective of the difference in muscular biting force and angular movement at the mandible of the patient; and to provide in an articulator means for compensating for the difference in muscular biting force and angular movement of the lower mandible of patients so that articulation may be accurately and readily accomplished in every instance.

The invention is shown by the way of illustration in the accompanying drawings in which,

Fig. 1 is a vertical elevational view of the articulator. Fig. 2 is a top plan view of the construction shown in Fig. 1. Fig. 3 is a fragmentary plan view of the stationary model support and guide plate; Fig. 4 is a side elevation of the construction shown in Fig. 3; Fig. 5 is a diagrammatic plan view showing the operation of the parts with the guide plate moved to one position; and Fig. 6 is a diagrammatic plan view similar to Fig. 5 showing operation of the parts with the guide plate moved to the opposite direction.

The illustrated embodiment of the invention comprises a frame 1 having sockets to receive the projecting portions of a triangular model support 2 and screws 3 are provided in the frame 1 for engaging these projecting portions and holding the support 2, securely in position. The model support 2 extends at substantially right angles from the frame 1 and is employed for holding the lower plate of a set of artificial dentures. Pivottally mounted on the upper part of the frame 1 is a model support 4 having a vertically depending guide pin 5 at the outer end thereof. The guide pin 5 is slidably mounted on the support member 4 and is

adapted to be held in adjusted position by a set screw 6 and slidably mounted on the guide pin 5 is a pointed block 7 which may normally be secured in a groove 8 by a set screw 9.

The model support 4 corresponds to the occlusal plane and has vertical outward and lateral swinging movements relatively to the stationary model support 2. Formed on the support 4 at the opposite end from the guide pin 5 are downwardly curved portions 10 corresponding to the human condyle paths or glenoid fossa, and projecting vertically from the frame 1 are pins 11 on which the downwardly curved portions 10 are guided and the pins 11 correspond to the condyles of the human anatomy. Connected to the support 4 rearwardly and to one side of the curved portions 10 are downwardly projecting pins 12 which project into recesses 13 formed in the frame 1.

The guide pin 5 is held in engagement with a guide plate 14 by means of a leaf spring 15 which is fixed to the frame 1 and engages the upper portion of the model support 4. The forward face of the guide plate 14 is preferably inclined to an angle of about 30 degrees to the occlusal plane represented by the upper model support 4 and is pivoted by means of a bolt 16 to the lower model support 2.

In using the above described articulator, the artificial dentures for the upper and lower jaws of the patient are supported on plaster models mounted on the model supports 4 and 2 respectively in a manner well known to the dental profession. Thereafter articulation is accomplished by moving the model support 2 relatively to the model support 4 and this movement is guided by the plate 14 over which the pin 5 is movable. In this manner the lower model support 2 is moved relatively to the occlusal plane represented by the upper model support 4 in accordance with the movement of the patient's mandible thereby to obtain proper articulation in the mouth.

The above operation is common practice and although it has provided satisfactory where the patient for whom the dentures are intended is of the average, such method does not obtain proper articulation for patients who are not included in this category. This fact will at once be apparent when it is realized that the greater number of persons bite with unequal muscular force on both sides and therefore if the dentures are articulated without making due compensation for this difference in muscular biting force, the dentures will not be comfortable to the patient and will not remain in place for any extended period of time because absorption will take place on the side which is subjected to the greater biting force.

This invention overcomes this difficulty

preferably by mounting the incisor guide plate 14 in such a manner that it may be adjusted to the right or left of its central position. The effect of swinging the plate 14 to the left is diagrammatically illustrated 76 in Fig. 5 which shows that in this position, movement on the left side is considerably greater than on the right because movement of the left condyle path member 10 is permitted a wide swing, but a slight amount of 75 movement is allowed to the right member 10 owing to the angular position of the guide plate.

It will be apparent that movement of the incisor guide pin 5 along the guide plate 14 80 in the usual manner for articulation will properly form the dentures relatively to each other when the biting force is greater on the right side than on the left when the plate is in the position indicated in Fig. 5. Of 85 course, the amount of adjustment of the guide plate 14 may be ascertained in any suitable manner as by trial or visual indication but this degree of movement can be readily determined as a practical matter 90 by one familiar with prosthetic articulation. By adjusting the plate 14 articulation may be accomplished for patients having a greater biting force on the left than on the right side (Fig. 6) as will readily be apparent.

Adjustment of the incisor guide plate to compensate for variations in muscular biting force has proved much simpler, more accurate and more reliable than adjustment of 100 the relative positions of the condyle members and condyle path which has heretofore been attempted because in the latter instance it is a difficult matter to effect delicate adjustment or to any practical degree of accuracy 105 to know how much adjustment is necessary for the desired articulation. By adjusting the incisor guide plate, adjustment is effected at the proper place and this is principally because movement mainly centers 110 around and is controlled by the incisor guide plate 14 at the point where movement is the greatest.

As heretofore mentioned the average inclination or angle of the incisor guide plate 115 14 is 30 degrees relatively to the occlusal plane but for different persons adjustment should be made because where the swinging movement of the mandible is short, the angle of condyle path is much greater and 120 where the manibular movement is relatively long the angle of the condyle path is less than 30 degrees.

In order to make due compensation for different conditions of this character, the 125 guide plate 14 is pivoted to swing in a vertical plane and for this purpose the plate may be formed in two separate parts which are held in assembled relation by a bolt 18 and a nut 19. By loosening the nut 19 the plate 130

14 may be swung to the desired position. In order to lock the plate in adjusted position a rearwardly extending ear 20 may be formed in the under side of the plate 14 and a set screw 21 in threaded engagement with the ear 20 may be moved against the under side of the model support 2. It will be apparent that downward pressure acting against the guide plate 14 will not operate to displace the guide plate from its adjusted position.

When it is found that the angle of the condyle paths of a patient is greater or less than 30 degrees, the guide plate 14 is first moved to its central position which arranges the model supports at central occlusion and then swung vertically upward or downward to increase or diminish the angle from the average in its relation to the occlusal plane. By means of the bolt 18, nut 19 and set screw 21, the plate 14 may then be securely held in its properly adjusted position and articulation of the dentures proceeded with. In cases where the angles of the condyle paths are unequal, then the guide plate 14 may be swung to the right or left on its pivot bolt 16 on an average plane of 30 degrees to the occlusal plane, the result will be that the incisal guide pin 5 will have an angular plane of less than 30 degrees on one side and greater than 30 degrees on the other.

While I have shown and described an embodiment of my invention as required by the statutes so that others skilled in this art may make and use the same, it is to be understood that the above is given merely for purposes of illustration and not of limitation, and numerous changes in details of design, arrangement and operation may be effected without departing from the spirit of the invention,

especially as defined in the appended claims.

What I claim as new and desire to secure by Letters Patent is:

1. In an articulator, a frame, upper and lower horizontally disposed supports extending at right angles from said frame, a guide plate having an inclined bearing surface carried by the free end of the lower support and further having its bottom formed to provide a rearwardly extending arm, a depending rod carried by the free end of the upper support adapted to engage the inclined surface of the guide plate, and means on the rearwardly extending arm of the guide plate to permit vertical adjustment thereof whereby to effect relative movement of the supports with respect to each other.

2. In an articulator having upper and lower horizontally disposed supports, a guide plate having an inclined bearing surface pivotally secured to the free end of the lower support, said plate further having a rearwardly extending arm disposed below said lower support, and a vertically disposed screw carried by the rearwardly extending arm contacting with the lower support whereby to effect adjustment of the bearing surface of the guide plate with respect to said lower support.

3. In combination with an articulator, a guide block having an inclined front face and a vertical rear face, a rearwardly extending arm forming a continuation of the bottom of the guide block and means carried by said arm adapted to contact with the articulator whereby to effect vertical movement of the guide block.

In testimony whereof, I have hereunto signed my name to this specification.
